FIG_2

FIG_3

FIG_4

FIG_5

FIG. 1 is a view in perspective of a column-supporting base showing the features of my new design;

FIG. 2 is a view in side elevation of the same;

FIG. 3 is a top plan view of the same;

FIG. 4 is a bottom plan view of the same;

FIG. 5 is an end view in elevation of the same, the opposite end being identical to the end shown;

FIG. 6 is a view in perspective of a modified form of the column-supporting base as shown in FIG. 1;

FIG. 7 is a view in perspective of a second modified form of the column-supporting base as shown in FIG. 1; and

FIG. 8 is a view in perspective of a third modified form of the column-supporting base as shown in FIG. 1.

The fragmentary broken line representation of a column in FIG. 1 is for purposes of illustration only.

I claim:

The ornamental design for a column-supporting base, substantially as shown and described.
